INSULATOR SUPPORTING BRACKET

Leon J. Olivier, New Orleans, La.

Application June 11, 1947, Serial No. 753,833

3 Claims. (Cl. 174—162)

1

This invention pertains to an improved form of bracket or support for insulators, and more particularly, to an improved form of a wire stringing, sagging, and supporting bracket.

In my Patent No. 2,302,883 entitled "Method of Stringing and Sagging Wires and Apparatus for Use Therein," I have shown a bracket of the general type involved. The bracket of the present invention provides a new and improved form of pivot support for the insulator pin.

In employing a bracket of the type herein involved, see particularly Figure 6 of the drawings, an insulator is loosely mounted on a spindle or bolt which is adapted, in an outwardly or horizontally extending position, to receive a cable or wire and to permit the wire to be uniformly sagged between poles. After the proper sagging has been effected, the wire may be secured to the insulator in the manner shown and the insulator is moved to a detachably locked vertical or angular position, such as shown in Figure 2 of the drawings. To remove the wire, the procedure is reversed.

In a bracket of this type, a suitable form of pivot mounting for the insulator supporting spindle or pin must be provided such that the insulator may be moved from one angular position to another, that the spindle may be detachably locked in its vertical position with respect to the bracket, that the spindle may be released from its locked vertical position and moved to a horizontal position, and that the spindle may be securely supported in the horizontal position when a wire or cable is being mounted on the insulator or removed therefrom.

It has thus been an object of my invention to provide a new and improved form of insulator bracket.

A further object has been to provide an insulator bracket having a simplified and improved type of pivot mounting for an insulator supporting pin or spindle.

A still further object of my invention has been to provide a less expensive and simplified form of bracket of the type involved which will provide for different angular positioning of an insulator pin or spindle.

These and other objects of my invention will appear to those skilled in the art from the drawings, specification and claims.

In the drawings, Figure 1 is a side view in elevation of a bracket employing my invention. A spool type of insulator is shown rotatably mounted on the bracket, and different angular positions of the insulator 25 and its associated sup-

2

porting pin or spindle 20 have been indicated by A, B, and C. The locked vertical position is indicated by the dotted lines of A, an unlatched intermediate position has been illustrated by the dotted lines of B, and a horizontal wire mounting or removing position is shown by the full lines of C.

Figure 2 is a side view in elevation showing the spindle at the position A of Figure 1;

10 Figure 3 is a front sectional view taken along the line III—III of Figure 2;

Figure 3A is a side view of a cotter pin that may be employed in connection with the bracket of my invention.

15 Figure 4 is a top plan view of the bracket of Figures 1 and 2;

Figure 5 is a horizontal sectional view taken along the line V—V of Figure 2;

20 Figure 6 is a perspective view in side elevation of the bracket of my invention and showing the insulator supporting spindle in a primarily or wire receiving position;

25 Figure 7 is a perspective view in elevation of a multiple insulator supporting bracket employing my invention.

Referring particularly to Figures 1 to 6, inclusive, the bracket of my present invention has a base or normally vertically extending back member 10 that may be provided with an opening 11 and suitable pressed out portions 12 for receiving a mounting bolt. A pair of outwardly and normally horizontally-extending spaced-apart supports 13 and 17 provide upper and lower arm members for an insulator supporting spindle, pin, or bolt 20.

35 The bracket of my present invention is similar in many respects to the bracket disclosed by the aforementioned patent. It includes a base or back member 10 that may be and preferably is

40 provided with a bolt-receiving aperture 11 and outwardly pressed lugs 12 for engaging a head of a bolt extending through the aperture 11. The base 10 carries a pair of insulator-supporting arms 13 and 17 which extend outwardly therefrom in parallel spaced relationship. When the bracket

45 is in use the base 10 normally extends vertically and the arms 13 and 17 extend horizontally, with the arm 13 located vertically above the arm 17. The arms are so spaced that the insulator supported by the bracket is normally located between them resting on the arm 17.

50 The upper arm 13 is similar in structural details to the corresponding arm of the bracket disclosed by said Patent 2,302,883. The outer end thereof is provided with a spindle receiving slot 16, thus

bifurcating the free end of the arm and forming spaced prongs 14 which extend in parallel relationship. Their outer ends are shaped so as to form a keeper for the head of an insulator pin or spindle 20 which forms a component part of the bracket. This is accomplished by so bending the outer end of each prong 14 that it extends upwardly, but slightly backwardly and terminates in a forwardly inclined upwardly projecting portion 15.

The slot 16 is slightly wider than the diameter of the spindle 20 and the inner end thereof is curved to correspond to the curvature of the cylindrical surface of the spindle engaged by it. The upwardly turned ends of the prongs 14 are adapted to engage the rectangular head 22 of the spindle 20 when the spindle is in place within the slot 16 and the head portion 22 thereof bridges and rests on the prongs 14. When the spindle is in this position it is latched or locked to the arm 13, by the "latch and keeper" relationship of the head 22 and the up-turned portions of the prongs 14.

While the lower arm 17 of my improved bracket corresponds in function to that of the corresponding arm of the bracket disclosed by my above mentioned patent, it is of simpler form, requires less metal in its formation and contributes to simplification of the bracket in other respects. As shown the arm 17 is provided with a spindle-receiving aperture 19 which is located vertically below the slot 16, is aligned therewith and is adapted to cooperate with that aperture in positioning the spindle 20 when the spindle is in its normal upright position. The arm 17 is provided with, or so formed as to provide a downwardly extending, substantially U shaped loop or spindle-receiving saddle 18, the upper surface of which is a continuation of the upper surface of the major portion of the arm but is looped downwardly so as to form a concave spindle-engaging surface which extends horizontally and longitudinally of the arm and also below the major portion of the arm a distance substantially equal to the diameter of the shank portion of the spindle 20.

The relationship of the saddle 18 to the major portion of the arm 17 is such that the aperture 19 is, in effect, transformed into a slot, although the inner edge 18' of the downwardly off-set portion or saddle 18 constitutes a bounding edge for the aperture. It will be noted that this edge 18' of the aperture extends transversely across the arm, is looped below the upper surface of the arm but, nevertheless, forms a continuation of the remaining portion of the edge of the aperture 19, which is curved to conform to the curvature of the cylindrical portion of the spindle 20 and is located immediately below and in alignment with the correspondingly curved portion of the edge of the slot 16.

As shown in the drawings, the lower end of the spindle 20 extends through the aperture 19 and the spindle is loosely or pivotally secured to the arm 17 by reason of the fact that a cotter pin extends through the portion, thereof located below that arm. An aperture extends diametrically through the lower portion of the spindle but is spaced from the lower end thereof, and a double hump cotter pin 21 is located therein. The cotter pin is of such length as to prevent the removal of the spindle from the arm 17 although the cotter pin is so located as to permit free movement of the spindle from the position A of Figure 1 through the position B to the position

C of that figure. In the last mentioned position the cotter pin 21 may engage the edge 18' of the saddle to position the spindle with relation to the saddle and a portion of the spindle, located between the pin 21 and the head 22, rests in the saddle, whereas the portion of the spindle between its normally lower end and the cotter pin rests against the lower face of the arm 17. When the spindle is so positioned it constitutes a cantilever support for the insulator carried by it and is held against lateral displacement by the lateral, upwardly sloped walls of the saddle 18.

In the normal or upright position of the spindle 20 the head portion 22 thereof is detachably latched to the upper arm 13 by the latch and keeper relationship between the head portion 22 and the upwardly turned ends of the prongs 14. In this position the spindle is held by the cooperation of the inner edge 18' of the saddle, the curved edge of the aperture 19, the curved edge of the slot 16 and the upwardly turned portions of the prongs 14. To unlock the spindle from this position it is forced upwardly so that its head 22 moves upwardly beyond the upwardly and in-turned portions of the prongs 14. The relationship between the parts is such that during this upward movement the upwardly extending prongs are flexed to permit the head to slide past them.

It will be noted that the structure of the lower arm 17 as here disclosed makes it possible to employ a spindle 20 having a cylindrical shank portion from the head end to the opposite end thereof. Such spindles are cheaper and more effective in operation than spindles such as are shown in my aforementioned patent and to this extent my improved bracket contributes to a further simplification of the insulator bracket as a whole. It will also be apparent that the arrangement of the saddle 18 disclosed, provides a more rugged and stiffer structure than is disclosed by said patent, with the result that each insulator spindle when functioning as a cantilever as disclosed in Figure 6 is capable of sustaining a relatively heavy load without the danger of distorting the bracket or any portion thereof.

In Figure 7, I have shown a multiple insulator bracket embodying my invention wherein a plurality of pairs of spaced-apart arm members 13 and 17 are positioned in a spaced-apart relationship along the base member 10.

As shown particularly in Figures 1 and 2, the cotter pin 21 is positioned to extend through the spindle 20, transversely of the bracket. The location of the pin 21 is preferably behind or to one side of the curved loop portion 18, and adjacent to such portion, in order that the spindle 20 may be raised and pivoted as indicated by the dot and dash lines of Figure 1. The cotter pin 21, as shown by the position C of Figure 1, lies transversely adjacent to the bottom surface of the arm 17 when the spindle 20 is in its horizontally extended position; it thus may serve to supplement the supporting action of the lower end of the spindle when the spindle is in its horizontal position.

Although for the purpose of illustrating my invention I have shown a particular form of a bracket, it will be apparent to those skilled in the art that various subtractions, additions and revisions may be made thereto without departing from its spirit and scope as indicated by the appended claims.

What I claim is:

1. An insulator-supporting bracket including a vertically extending base, upper and lower hori-

zontally extending arms secured thereto and an insulator-supporting spindle pivotally connected to the lower of said arms and movable from a horizontal position to a vertical position in engagement with the upper arm to position the insulator carried thereby between said arms; characterized by said lower arm has a spindle-receiving aperture formed therein adjacent the free end thereof and is provided with a transversely extending downwardly looped, U-shaped saddle forming a closure for said aperture at the free end of the arm side thereof and having a concave spindle-engaging upper surface constituting a continuation of the upper surface of the major portion of said lower arm and extending horizontally longitudinally of said arm and downwardly below the major portion of said arm an amount substantially equal to the diameter of the portion of the spindle engaged thereby.

2. An insulator-supporting bracket including a vertically extending base, upper and lower horizontally extending arms secured thereto and an insulator-supporting spindle pivotally connected to the lower of said arms and movable from an extended horizontal position to a vertical position in engagement with both the lower and upper arms to position the insulator carried by said spindle between said arms; characterized by that said lower arm has a spindle-receiving aperture formed therein intermediate the ends thereof and is provided with a transversely extending, downwardly looped U-shaped saddle constituting an extension of said arm and having a concave spindle-receiving upper surface forming a continuation of the upper surface of the major portion

of said arm, extending longitudinally of said arm and below the major portion thereof a distance substantially equal to the diameter of the portion of said spindle engaged thereby.

- 5 3. An insulator support bracket including a base portion, upper and lower arms formed integrally therewith and extending at right angles thereto and an insulator-supporting spindle movably connected to the lower of said arms and movable
- 10 from a horizontal position longitudinally of such arm to an upright position in engagement with both the lower and upper arms, wherein the insulator carried thereby is located between said arms; characterized by that said lower arm has
- 15 a spindle-receiving aperture formed therein intermediate the ends and sides thereof and is provided with a downwardly off-set, transversely extending portion located immediately adjacent said aperture having a concave spindle-receiving surface forming a continuation of the upper surface of the major portion of the bracket and extending below the major portion of said arm a distance substantially equal to the diameter of said spindle, with the inner edge of said off-set portion constituting a downwardly looped portion of the edge of said aperture.
